EXHAUST BLOWER UNIT FOR COOKING
STOVE HOODS

Henry N. Butler, Dallas, and Thomas A. Sibley,
Jr., Garland, Tex.; said Butler assignor to Jack
D. Carpenter, Dallas, Tex.

Application January 14, 1949, Serial No. 232

Term of patent 14 years

(Cl. D81—26)

To all whom it may concern:

Be it known that we, Henry N. Butler and Thomas A. Sibley, Jr., citizens of the United States of America, residing at Dallas and Garland, respectively, in the county of Dallas and State of Texas, have invented a new, original, and ornamental Design for an Exhaust Blower Unit for Cooking Stove Hoods, of which the following is a specification, reference being had to the accompanying drawing, forming part thereof.

Figure 1 is a front elevational view of an exhaust blower unit for cooking stove hoods, showing our new design.

Figure 2 is a top plan view thereof, and

Figure 3 is a perspective view thereof, both sides being identical.

We claim:

The ornamental design for an exhaust blower unit for cooking stove hoods, substantially as shown and described.

HENRY N. BUTLER,
THOMAS A. SIBLEY, JR.
